THE NORRIS PETERS CO., PHOTO-LITHO., WASHINGTON, D. C.

UNITED STATES PATENT OFFICE.

JOHN W. FLEMING, OF NEW YORK, N. Y.

FLUE-STOPPER.

SPECIFICATION forming part of Letters Patent No. 629,244, dated July 18, 1899.

Application filed December 14, 1898. Serial No. 699,230. (No model.)

To all whom it may concern:

Be it known that I, JOHN W. FLEMING, of the city of New York, borough of Brooklyn, in the county of Kings and State of New York, 5 have invented a new and useful Improvement in Flue-Stoppers, of which the following is a full, clear, and exact description.

The object of my invention is to provide a stopper especially adapted to close ends of 10 boiler-flues and so constructed that the stopper may be applied and the flue perfectly closed while the boiler is in use.

Another object of the invention is to so construct the stopper that it may be quickly and 15 accurately applied.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a horizontal longitudinal section 25 taken on the line 1 1 of Fig. 2. Fig. 2 is a transverse section on the line 2 2 of Fig. 1. Figs. 3 and 4 are detail perspective views of the sections of the body of the stopper, and Fig. 5 is a side elevation of the key employed 30 in connection with the stopper.

The body of the stopper consists, preferably, of two solid semispherical sections A and B. Each section is provided with a central longitudinal groove C. The grooves are arranged 35 to register when the sections of the body are brought together and are of the same formation. The side walls 10 of the grooves C are tapering or converging at one end 11 of the body-section in which the groove is produced, 40 and the back wall of the groove is inclined in a direction that renders the groove deepest at its contracted end. Thus when the body-sections are brought together a circular opening 12 is formed at the outer end of the complete 45 body, while an oval opening 13 is provided at the inner end of the body.

The space formed by the registering grooves is adapted to receive a key D, having a cylindric outer part 14 and a wedge-shaped inner 50 part 15, flattened at opposite sides, and the greater portion of the outer cylindric part 14

is exteriorly threaded. Before the body-sections A and B are brought together the wedge-shaped part 15 of the key and a portion of the cylindric part 14 are placed in the groove C 55 of one of the sections, the longitudinal section of the wedge-shaped part of the key engaging with the back wall of the groove. When the stopper is to be placed in a flue E, the wedge-shaped part 15 of the key projects 60 beyond the inner end of the stopper sufficiently to permit the sections of said stopper to be brought close together, in which position of the two sections the stopper may readily enter the tube. 65

When the stopper-body is properly placed in the tube, the threaded part of the key extends beyond the adjacent end of the tube and through an opening in a cap F, the said cap comprising a plug portion 16 and flange 70 17. The plug portion of the cap is adapted to engage with the interior of the tube near the end, while the flange extends laterally beyond and is adapted to contact with the tube at its end, as shown in Fig. 1. The sections of the body are expanded within the tube and the cap is held as a stopper at the end of the tube by adjusting a nut 18 on the threaded end of the key to a firm bearing against the cap or against a washer 19, intervening the cap and the nut. The inner surface of the flange 17 is annularly grooved, as at 17^a, to receive the end of the flue, said groove being concave, so that the cap may be forced tightly against the inner edge of 80 85 the flue end when pressure is applied to the nut 18.

The sections of the stopper-body when brought together are prevented from having end movement by abutment-pins 20 21 at the 90 inner ends of the stopper-sections, each pin bearing against the adjacent end of the stopper-section toward which it projects, as shown in Fig. 2.

Having thus described my invention, I 95 claim as new and desire to secure by Letters Patent—

1. A flue-stopper, comprising a body formed of longitudinal sections, a key having a wedge-shaped portion adapted to be located between the body-sections, a cap through which a portion of the key passes, and a device 100

adapted for the adjustment of the key and as a lock for the cap, as and for the purpose specified.

2. A flue-stopper comprising a body constructed in longitudinal sections, each section being provided with a correspondingly-located groove, each groove having tapering side walls and an inclined bottom wall, the grooves being deepest at their contracted ends, a key provided with a threaded and a wedge-shaped section, the wedge-shaped section of the key being adapted to enter the grooves in the body-sections, a cap through which the threaded portion of the key passes, and means for expanding the body-sections through the medium of the key, and a locking device for the cap, as described.

3. In a flue-stopper, the combination, with a body constructed in two longitudinal sections, said sections being provided with registering tapering grooves, and means for holding the sections of the body against end movement, of a cap, a key having a threaded part

that passes through the cap and a wedge part adapted to enter the registering grooves in the body-section, and a nut located upon the threaded end of the said key, being adapted to bear against the outer portion of the said cap, for the purpose set forth.

4. A flue-stopper comprising a body formed of two longitudinal sections, a cap consisting of a body adapted to enter a flue, and a flange having a peripheral groove adapted to receive the end portion of a flue, a key having a wedge-shaped portion adapted to be located between the end sections and expand the same, the said key being provided with a threaded portion arranged to pass through the cap, and a lock-nut carried by the threaded portion of the key and adapted to bear against the said cap, for the purpose set forth.

JOHN W. FLEMING.
